KEY RETAINER

Samuel Segal, Brooklyn, N. Y.

Application December 20, 1941, Serial No. 423,860

8 Claims. (Cl. 224—28)

This invention has to do with a key retainer adapted to be disconnectably mounted about the wrist of a wearer and has for its object to provide an improved and serviceable key retainer wherein a pair of spaced straps carry time keeping means and wherein one of the straps is utilized to swingably support yoke means rotatably and disengageably carrying a guard rotatably straddled by a locking bar at one end thereof and wherein the yoke means rotatably and disconnectably carries at another end thereof suitable key means provided with a loop portion for threadably receiving the other strap of the pair of straps to interlock with a lip of the guard prior to its retention by the locking bar flatwise against the guard. Another object is to utilize an intervenor carried by one of the strap members to shield the key from the wearer of the key retainer. Other important objects will be apparent from the following detailed disclosure considered in connection with the accompanying drawing wherein:

Fig. 1 is a perspective view of the key retainer according to my invention.

Fig. 2 is a fragmentary front elevational view of the key retainer.

Fig. 3 is a sectional view on the line 3—3 of Fig. 2, however illustrating the locking strap member buckled.

Fig. 4 is a fragmentary perspective view of the key retainer showing the rotatable key extended for use, and

Fig. 5 is an exploded view of the buckle on which the rotatable key, guard, and swingable locking bar are mounted.

In the drawing, the key retainer broadly designated R comprises the flexible leather strap members 10 and 11 appropriately sustaining wrist watch 12.

One end of the strap member 11 is provided with spaced sockets or loops 13 characterizing bearing means rotatably supporting bridge 14 of the U shaped hasp or yoke 15 of the buckle broadly denoted B.

Rotatably interposed between the arms 16 of the hasp 15 is the U shaped guard G having its arms 17 provided with the laterally extending studs or pintles 18 on which the depending perforated legs 19 of the swingable U shaped locking bar 20 are rotatably and disconnectably mounted, the pintles or trunnions 18 being rotatably but removably retained or journaled in the openings or bearings 21 in sides 16 of the hasp 15, the sides or arms 16 straddling legs 19 of the

locking bar 20, and legs 19 rotatably straddle arms 17 of the guard G.

It will be observed that the arms 16 of hasp or yoke 15 include the offset terminals 22 provided with the inwardly extending studs 23 removably and rotatably fitting into the bearings or openings 24 in the sides of the bow or head 25 of the key K having the notched and grooved shank 26.

10 Where the leather strap members 10 and 11 are surrounding the wrist of the wearer, the shank 26 is against the leather and liftable closure flap 27 having one end 28 stitched at 29 to the strap member 11, flap 27 extending along the 15 length of the key and constitutes an intervenor to shield the skin against the metal of the swingable key. However the key in its closed or inoperative relation is held concealed between flap 27 and the terminal 30 of the strap member 10 20 threaded through the hollow bow or rim 25 of the key.

If terminal 30 is threaded through the bow 25 one of the perforations 31 is adapted to receive the offset lip or tongue 32 extending from the bridge 33 of the guard or yoke G to removably interlock therewith.

Thereafter terminal 30 is brought over to lie adjacent the arms 17 of the guard by threading thereof through the rockable or pivoted locking bar 20. It follows that the swingable key is snugly retained within the buckle and between the protecting flap 27 and the terminal 30 of strap member 10. With the key concealed between inner flap 27 and outside terminal 30, the swingable guard G likewise is retained against movement between the key and the outside terminal 30. Thus the guard G serves as a stop for the key.

To render the key accessible for use terminal 40 30 is unthreaded or removed from the locking bar 20 and one of the openings 31 interlocking with lip 32 is withdrawn from the latter permitting terminal 30 to be subsequently withdrawn from the loop or bow 25 of the key. Hence buckle B 45 may be tilted away from the wrist and relative to sockets 13.

Access thereafter may be had to the key and the latter is bodily swung to the position illustrated in Fig. 4, that is, so that its shank overhangs the buckle, the guard G in this instance serving as stop means for the key at which time indentation 34 of lip 32 is disposed between and in the gap defined by the brace or bridge members 35 and 36 of the loop or bow 25.

Where the key is rotated to be outside of the

buckle (Fig. 4), the guard and more particularly lip 32 and bridge 33 thereof abut the shank of the key and bridge 35 of the bow of the key respectively when thumb pressure is applied to the guard, hence the key is held substantially in longitudinal alignment with the buckle which in this instance characterizes a handle for the swingable key to facilitate convenient rotation thereof.

As shown the buckle is of suitable metal, that is, its yoke 15, guard G, and the locking bar 20 each is of metal having adequate resiliency whereby arms 16 may be slightly sprung apart to disconnectably receive the pintles 18 of the guard and to permit studs 23 to enter the bearings 24 of the bow of the key. The arms 17 of the guard also are slightly resilient to permit legs 19 of the rotatable locking bar 20 to be removably snapped over pintles 18 of the guard. However when the several parts of the buckle are assembled they are prevented from accidental disengagement.

By the present arrangement, the buckle of the key retainer may be readily assembled or knocked down and in the assembled relation, the key retainer of which the buckle is a part, an emergency key may be desirably held concealed but instantly available for use when necessary.

Various changes may be made in the details of construction and arrangement of parts without departing from the spirit of the invention or sacrificing any of the advantages thereof inherent therein.

I claim:

1. A key retainer for supporting a key comprising a strap member having bearing means, a yoke rotatably sustained by said bearing means and including spaced arms, a guard interposed between said arms, said guard and arms having means for rotatably supporting said guard, a locking bar mounted on said guard, said arms and key having means for rotatably sustaining said key, said key having a bow including an opening, a lip extending from said guard across said opening and overlying said bow to limit rotational displacement of said guard towards said key and a perforated strap member adapted to be threaded through said opening for interlocking with said lip and adapted to overlie said guard and disengageably fastened by said locking bar.

2. A key retainer for supporting a key comprising a strap member having bearing means, a yoke rotatably sustained by said bearing means and including spaced resilient arms, a guard interposed between said arms, said guard and arms having means rotatably sustaining said guard, a locking bar straddling said guard and straddled by said arms, means for rotatably sustaining said bar relative to said yoke and guard, said arms and key having means for rotatably sustaining said key, said key including a bow having an opening, a lip extending from said guard across said opening for overlying said bow to limit rotational displacement of said guard towards said key, and a perforated strap member adapted to be threaded through said opening for interlocking with said lip and adapted to overlie said guard and disengageably fastened by said locking bar.

3. A key retainer for removably encompassing a wrist of a wearer and for supporting a key comprising a strap member having bearing means, a yoke having a bridge rotatably sustained by said bearing means and including

spaced arms extending from said bridge, a guard interposed between said arms, said guard and arms having means for rotatably supporting said guard, a locking bar straddling said guard and straddled by said arms, means rotatably supporting said bar, said arms and key having means for rotatably sustaining said key, said key having a bow including an opening, a lip extending from said guard across said opening for overlying said bow to limit rotational displacement of said guard towards said key, a perforated strap member adapted to be threaded through said opening for interlocking with said lip and adapted to overlie said guard and disengageably fastened by said locking bar, and a flap attached to said first mentioned strap member and disposed along one face of said key to constitute an interventer shield between said key and the flesh of said wrist.

4. A key retainer for supporting a key comprising a strap member having bearing means, a yoke having a bridge rotatably sustained by said bearing means and including spaced arms having spaced bearings adjacent said bridge, a guard interposed between said arms and having trunnions rotatably sustained by said bearings, a locking bar straddling said guard and straddled by said arms and rotatably sustained by said trunnions, said key having a bow including an opening, said arms and key having means independent of said trunnions for rotatably sustaining said bow, a lip extending from said guard across said opening for overlying said bow to limit rotational displacement of said guard towards said key, and a perforated strap member adapted to be threaded into said opening for interlocking with said lip and adapted to overlie said guard and disengageably fastened by said locking bar.

5. A key retainer for supporting a key comprising a strap member having bearing means, a yoke having a bridge rotatably sustained by said member and including spaced arms having spaced bearings adjacent said bridge, a guard interposed between said arms and having trunnions rotatably sustained by said bearings, a locking bar straddling said guard and straddled by said arms and rotatably sustained by said trunnions, said key having a bow including an opening, said arms and key having means independent of said trunnions for rotatably sustaining said bow, a lip extending from said guard across said opening for overlying said bow to limit rotational displacement of said guard towards said key, a perforated strap member threadable through said opening for interlocking with said lip and adapted to overlie said guard and disengageably fastened by said locking bar, and a flap secured to said first mentioned strap member for shielding said key.

6. A key retainer for removably encompassing a wrist of a wearer and for supporting a key comprising a strap member having bearing means, a yoke having a bridge rotatably sustained by said bearing means and including spaced resilient arms having spaced bearings adjacent said bridge, a guard interposed between said arms and having laterally extending trunnions rotatably and removably sustained by said bearings, a locking bar straddling said guard and straddled by said arms and rotatably and removably sustained by said trunnions, said key having a hollow bow including an opening, said arms having offset portions, the latter and said key having means independent of said trunnions

for rotatably and removably sustaining said bow, a lip projecting from said guard and extending medially of and across said opening to overlie said bow to limit rotational displacement of said guard towards said key, a perforated strap member adapted to be threaded through said opening for interlocking with said lip and adapted to overlie said guard and disengageably fastened by said locking bar, and a liftable flap secured to said first mentioned strap member and disposed along one face of said key to constitute an interventer shield between said key and the flesh of said wrist.

7. In a key retainer for supporting a key comprising a strap member including bearing means, a U-shaped yoke having a bridge rotatably sustained by said bearing means and including spaced and resilient arms including spaced bearings adjacent said bridge, a U-shaped guard having spaced arms including extended means rotatably and removably sustained by said bearings and having a bridge portion, a locking bar rotatably and removably mounted on said extended means, said key having a bow including an opening, said bow and said first mentioned arms having means for rotatably sustaining said key, a lip extending from said bridge portion and projecting across said opening and cooperating with said bow to hold said key in said yoke, and

a perforated strap member threadable into said opening for interlocking with said lip and adapted to overlie said guard and disengageably fastened by said locking bar.

5. 8. In a key retainer for supporting a key comprising a strap member including bearing means, a yoke having a bridge rotatably sustained by said bearing means and including spaced and resilient arms having spaced bearings adjacent 10 said bridge, a guard interposed between said arms and having means rotatably engaged in said bearings, a locking bar, means rotatably and disconnectably sustaining said bar on said guard, said key having a bow including an opening, said key and arms having means rotatably and disconnectably sustaining said key, a lip extending from said guard across said opening for overlying said bow to limit rotational displacement of said guard towards said key, a perforated strap member 15 threadable into said opening for interlocking with said lip and adapted to overlie said guard and disconnectably fastened by said locking bar, and a flap secured to said first mentioned strap member, said bow limiting displacement of said lip towards said key and said flap limiting displacement of said key in a direction away from said guard.
